UNITED STATES PATENT OFFICE.

FRANK W. JACOBS, OF PLYMOUTH, IOWA.

APPARATUS FOR HOISTING AND CONVEYING BOULDERS.

SPECIFICATION forming part of Letters Patent No. 595,713, dated December 21, 1897.

Application filed November 28, 1896. Serial No. 613,840. (No model.)

To all whom it may concern:

Be it known that I, FRANK W. JACOBS, a citizen of the United States of America, residing at Plymouth, in the county of Cerro

5 Gordo and State of Iowa, have invented a new and useful Portable Machine for Moving Boulders, &c., of which the following is a specification.

My object is to provide a machine specially 10 adapted for lifting boulders and building stone fences and lifting and moving other heavy objects from one place to another.

My invention consists in the arrangement and combination of operative mechanism 15 upon a carriage adapted therefor, as herein-after set forth, pointed out in my claims, and illustrated in the accompanying drawings, in which—

Figure 1 is a top view of the machine. Fig. 20 2 is a side elevation showing the traction-wheels removed. Fig. 3 is a perspective view of the machine in position as required in practical use in placing boulders in a stone fence.

Referring to the accompanying drawings, 25 the reference-letter A is used to indicate the front axle of the machine. A tongue may be pivoted thereto in an ordinary way, and an upright A² is also pivotally attached thereto by means of a swivel A³, as shown in Fig. 3, 30 and inclined a slight degree from the vertical in a rearward direction.

The rear axle B is arched and made much longer than the front axle. Hence the machine may be readily backed over the end of 35 a fence or other large objects. A beam B² is extended transversely of the machine above said rear axle. Two side beams B³ are fixed to the end portions of the beam B² and extended horizontally forward to the upright A², 40 near its central portion, and reinforcing-braces B⁴ are fixed to the top of said upright A² and to the rear corner of the frame to provide a frame that is strong enough to support great weights at its central portion. The combination of the braces B⁴ with the top of the 45 post A² and the rear ends of the beams B³ and rear corners produces a truss.

C is a windlass mounted in suitable bearing-boxes on the top, central portion of the 50 side beams B³ and extended transversely of the machine-frame at an angle relative to the axle B and beam B², and has a large wheel C².

Guide-blocks C³ are fixed to the side surfaces of the wheel to project beyond the edge thereof and have their edges beveled to serve as 55 ratchet-teeth.

D is a spring-actuated bar slidably mounted in suitable bearings D² on the side beams B³ with one end normally held in engagement with the side of the wheel C² to engage the 60 blocks on the sides of the wheel. A lever D⁴, fulcrumed to the machine-frame and extended to the front of the machine-frame, may be conveniently grasped to hold the bar from disengagement with the blocks on the 65 wheel while the wheel is in operation.

F is a rope or cable fixed to the wheel C² and wound thereupon, and H is a chain wound upon the windlass, and a grapple H² is attached to the free end of the chain. This 70 grapple may be of any ordinary construction adapted to engage irregular-shaped stones.

In practical use the entire device is moved over a field by draft-animals, and by reason of the peculiar shape of the frame the arched 75 rear axle is easily placed in position directly over the stone to be moved and free access to the stone provided on the side opposite from the wheel C² on account of the inclined position of the winch relative to the rear axle. 80 The grapple is then secured to the stone in the ordinary way and the beam detached from the tongue and secured to the stone in the ordinary way, and the team detached from the tongue and secured to the rope or 85 cable upon the wheel C². As the draft-animals advance the wheel and its axle are rotated and the stone elevated. The stop device connected with the wheel secures it in any position in which it may be placed. The 90 draft-animals are then secured to the tongue and the machine moved to the spot where the stone is to be deposited. The lever D⁴ is then operated to release the wheel and winch and the stone lowered to its place by gravity. 95

Having thus described my invention, what I claim as new therein, and desire to secure by Letters Patent of the United States therefor, is—

1. In a machine for moving boulders and 100 the like, the carriage-frame consisting of an arched axle, a straight beam fixed across its top, a short front axle, a post pivotally connected therewith by means of a swivel-cou-

ling, a swivel-coupling, beams fixed to the post at their front ends and to the ends of the beam on the rear axle to extend horizontally and braces fixed to the top of the post and the 5 rear end corners of the carriage-frame, all arranged and combined for the purposes stated.

2. In a machine for moving boulders and the like, the carriage-frame consisting of an arched axle, a straight beam fixed across its 10 top, a short front axle, a post pivotally connected therewith by means of a swivel-coupling, a swivel-coupling, beams fixed to the post at their front ends and to the ends of the beam on the rear axle to extend horizontally 15 and braces fixed to the top of the post and the rear end corners of the carriage-frame, a winch in bearings fixed to the horizontal beams to extend at an angle relative to the rear axle and means for operating the winch, all arranged 20 and combined for the purposes stated.

3. A machine for moving boulders and the like comprising a carriage consisting of a short

front axle A, wheels on its ends and a pole at its center, a post A² pivotally connected with the axle, a swivel-coupling A³, an arched axle 25 B and wheels on the ends of the axle, a beam B² fixed on top of the arched axle, beams B³ fixed to the pivoted post and to the beam on the rear axle, braces fixed to the top of the pivoted post and the rear corners of the carriage-frame, a winch C mounted on the frame 30 to extend at an angle to the rear axle, a wheel C², fixed blocks C³ on its side faces, a spring-actuated bar D in bearings D² fixed to the beams B³ to engage the said blocks and a lever 35 for operating said bar, and a rope for operating the winch, all arranged and combined in the manner set forth for the purposes stated.

FRANK W. JACOBS.
